LEVER ACTUATED LATCH BOLT

Jack Croft, Cisco, Tex.

Application June 6, 1950, Serial No. 166,481

3 Claims. (Cl. 292—111)

1

This invention relates to devices for drawing and locking elements together, and in particular a latch having a housing with a latch bolt longitudinally slidable therein, held outwardly by a spring and actuated by a lever that snaps over the center, and a keeper over which the outer end of the latch bolt snaps to secure the parts in assembled relation.

The purpose of this invention is to provide a snap bolt of the quick acting type for drawing and clamping sections of building panels, concrete forms, rafters, trusses, tongue and groove elements, and other objects together wherein the parts are forced into assembled relation by a lever action and secured in assembled relation by forcing the lever over the center.

Sections of concrete forms, paneling, and other devices are secured together by bolts and clamps which, with the conventional type of fastening, requires considerable time and the reuse thereof is difficult. With this thought in mind this invention contemplates a lever actuated snap latch where a jaw on the outer end of the latch bolt snaps over a keeper and the parts are drawn together by a lever action which automatically locks the parts in assembled relation.

The object of this invention is, therefore, to provide a lever action latch that is so constructed that with a jaw on the outer end of the latch placed over a keeper parts upon which the elements are mounted may readily be drawn together, locked in assembled relation, and also readily released.

Another object of the invention is to provide a latch bolt of the type that may readily be attached to meeting or adjoining edges of panels and the like of objects and devices of different types and designs.

A further object of the invention is to provide a lever actuated latch bolt for drawing and clamping meeting edges of objects and devices which is of a simple and economical construction.

With these and other objects and advantages in view the invention embodies a housing having flanges extended upwardly from a base with a latch bolt carried by the flanges and with a lever pivotally mounted on the bolt and positioned to draw a jaw on the outer end of the bolt against a keeper on the edge of an adjoining panel or device whereby the parts are drawn together with considerable force and in which the parts are locked in the assembled relation by the inner end of the lever passing over the center of the bolt.

Other features and advantages of the invention

2

will appear from the following description taken in connection with the drawings wherein:

Figure 1 is a plan view showing the improved latch bolt with parts shown in section.

Figure 2 is a side elevational view of the latch bolt shown in Figure 1 taken on line 2—2 of Figure 1 and also with part shown in section.

Figure 3 is a similar view showing the parts partly assembled and with the jaw of the latch bolt sliding over the upper end of the keeper.

Figure 4 is a similar section showing the parts in the locked positions.

Figure 5 is an end elevational view taken on line 5—5 of Figure 2 showing the end of the latch housing with the bolt thereof shown in section.

Figure 6 is a similar view taken on line 6—6 of Figure 2.

Figure 7 is a detail through the outer end of the base of the latch taken on line 7—7 of Figure 2.

Figure 8 is a detail showing a trunnion for pivotally mounting the lever on the latch bolt.

Figure 9 is a plan view of the lever that actuates the latch bolt.

Figure 10 is a longitudinal section similar to that shown in Figures 2 and 3 illustrating the latch bolt elevated to the releasing position.

Referring now to the drawings wherein like reference characters denote corresponding parts the improved lever actuated latch of this invention includes a bolt 10 having a threaded stem 11, a U-shape lever 12, a spring 13, and a keeper 14.

The bolt 10 is provided with a jaw 15 on the outer end and the jaw is positioned to snap over a projection 16 on the keeper 14 when locking the parts in assembled relation. The lock bolt 10 is slidably mounted in a slot 17 in a flange 18 at the end of the outer section 19 of the base and, as shown in Figure 2 the base is provided with an inner section 20 with the intermediate part bent upwardly and downwardly with a U-bend forming sections 21 and 22 of a U-shape flange. The stem 11 of the bolt 10 extends through a slot 23 in the flange formed by the sections 21 and 22 and the section 20 of the base is also provided with a flange 24 which is provided with an opening 25 through which the stem 11 extends as shown in Figures 2 and 7. A nut 26 is provided on the outer end of the stem 11 and with the nut threaded on the stem the position of the jaw 15 is adjustable.

A trunnion 27 is also threaded on the stem 11 and pinions 28 and 29 extended laterally from

55

the trunnion extend through openings 30 and 31, respectively in the arms 32 and 33 of the lever 12. The inner ends of the arms 32 and 33 are provided with yokes 34 and 35 in which rollers 36 and 37 are mounted on bolts 38 and 39, respectively. The trunnion 27 is held between nuts 40 and 41 whereby the trunnion is positioned so that with the rollers 36 and 37 extended straight downwardly the latch bolt is forced forwardly by the spring 13 so that the jaw 15 on the outer end thereof may snap over the keeper 14 as parts upon which the keeper and latch are mounted are brought together, or as illustrated in Figures 2 and 3 a tongue 42 is inserted in a groove 43, the tongue extended from a board or panel 44 and the groove being positioned in a board or panel 45.

When the jaw 15 is latched over the keeper 14 the lever 12 is forced downwardly to the position shown in Figure 4 whereby the rollers 36 and 37 pass upwardly on the outer section of the intermediate flange and with the rollers extended upwardly above the center of the stem 11, as illustrated in Figure 4 the latch will be locked in the holding position.

The latch base is covered by a substantially U-shape cover 46 and the base is secured to the panel 44 by bolts 47, 48, 49 and 50 and the keeper 14 is secured to the panel 45 by a bolt 51.

The keeper is provided with a beveled tongue 52 and the base 19 of the inner section is provided with a corresponding bevel surface 53 wherein, as illustrated in Figure 10 the bevel surface 53 is pressed against the surface 52 with the parts assembled.

The spring 13 is positioned around the stem 11 of the latch bolt 10 and the large end of the spring is positioned against the section 21 of the intermediate flange of the base. The opposite or small end of the spring is positioned against a washer 54 that is positioned against a shoulder 55 of the latch bolt.

With the parts arranged in this manner the elements upon which the keeper and latch are positioned are brought together until the jaw 15 snaps over the keeper 14 and with the parts in this position the lever 12 is forced downwardly to the position shown in Figure 4 whereby the elements are securely locked together. The parts will remain in this position until the outer end of the lever 12 is forced upwardly to release the latch bolt 10.

The lever 12 or pivot arm snaps over the center and also remains in the free or released position or in the position of holding the lock bolt released as shown in Figure 10, until it is manually actuated.

It will be understood that modifications may be made in the design and arrangement of the parts without departing from the spirit of the invention.

What is claimed is:

1. In a lever actuated latch adapted to cooperate with a keeper, the combination which comprises a base having spaced perpendicularly disposed flanges with slots and openings therein, a latch bolt having a gripping jaw on the outer end and a threaded stem extended from the opposite end slidably mounted in the slots and openings of the flanges of the base, said latch bolt having a shoulder at the intersection of the latch bolt and stem, a spring positioned around the stem with one end against the said shoulder and the other positioned against one of the flanges of the base, said keeper positioned to be engaged by

the jaw on the outer end of the latch bolt, a nut adjustably mounted on the opposite end of the stem of the latch bolt for adjusting the limit of the outward movement of the latch bolt, and a lever carried by and pivotally mounted on the latch bolt and positioned to engage an intermediate flange of the base for urging and locking the latch bolt in the locking position.

2. In a lever actuated latch adapted to cooperate with a keeper, the combination which comprises a base having spaced perpendicularly disposed flanges with slots and openings therein, a latch bolt having a gripping jaw on the outer end and a threaded stem extended from the opposite end slidably mounted in the slots and openings of the flanges of the base, said latch bolt having a shoulder at the intersection of the latch bolt and stem, a spring positioned around the stem with one end against the said shoulder and the other positioned against one of the flanges of the base, said keeper positioned to be engaged by the jaw on the outer end of the latch bolt, a nut adjustably mounted on the opposite end of the stem of the latch bolt for adjusting the limit of the outward movement of the latch bolt, a trunnion threaded on the stem having laterally disposed pins, nuts threaded on the stem and positioned against opposite sides of the trunnion, a U-shape lever having arms with rollers in the ends thereof and having openings spaced from the ends in which the pins of the trunnion are positioned whereby with downward movement of the outer end of the lever the rollers travel across the center of the latch bolt securing the bolt in the locking position.

3. In a lever actuated latch adapted to cooperate with a keeper, the combination which comprises a base provided with spaced perpendicularly arranged flanges having slots and openings therein, a latch bolt having a gripping jaw on the outer end and a threaded stem extended from the opposite end slidably mounted in the slots and openings of the flanges of the base, said latch bolt having a shoulder at the inner section of the latch bolt and stem, a spring positioned around the stem with one end against the shoulder and the other positioned against one of the flanges of the base, a nut adjustably mounted on the opposite end of the stem of the latch bolt for adjusting the limit of the outward movement of the latch bolt, a trunnion threaded on the stem having laterally disposed pins, nuts threaded on the stem and positioned against opposite sides of the trunnion, a U-shaped lever having arms with rollers in the ends thereof and having openings spaced from the ends in which the pins of the trunnion are positioned whereby with downward movement of the outer end of the lever the rollers travel across the center of the latch bolt to thereby secure the bolt in locked position.

JACK CROFT.
